(57) **CLAIM**

The ornamental design for a wire clamp, as shown and described.

DESCRIPTION

FIG. 1 is a perspective view of a clip of a wire clamp, in accordance with the present design;

FIG. 2 is a front side view of the wire clamp shown in FIG. 1;

FIG. 3 is a left side view of the wire clamp shown in FIG. 1;

FIG. 4 is a top side view of the wire clamp shown in FIG. 1;

FIG. 5 is a bottom side view of the wire clamp shown in FIG. 1;

FIG. 6 is a perspective view of a top piece of the wire clamp shown in FIG. 1;

FIG. 7 is a front side view of the top piece of the wire clamp shown in FIG. 6;

FIG. 8 is a left side view of the top piece of the wire clamp shown in FIG. 6;

FIG. 9 is a top side view of the top piece of the wire clamp shown in FIG. 6;

FIG. 10 is a bottom side view of the top piece of the wire clamp shown in FIG. 6;

FIG. 11 is a perspective view of a bottom piece of the wire clamp shown in FIG. 1;

FIG. 12 is a front side view of the bottom piece of the wire clamp shown in FIG. 11;

FIG. 13 is a left side view of the bottom piece of the wire clamp shown in FIG. 11;

FIG. 14 is a top side view of the bottom piece of the wire clamp shown in FIG. 11;

FIG. 15 is a bottom side view of the bottom piece of the wire clamp shown in FIG. 11; and,

FIG. 16 is a perspective view of the wire clamp shown in FIG. 1 in an environment of use.

Right side and back side views of the: (a) wire clamp; (b) top piece of the wire clamp; and (c) back piece of the wire clamp

(Continued)

are omitted because they are respectively symmetrical to the left side and front side views. The broken lines shown in FIGS. 5 and 15 do not form part of the claimed design. The broken lines shown in FIG. 16 depict the environment in which the wire clamp is used and do not form part of the claimed design.
